ATTORNEY.

UNITED STATES PATENT OFFICE.

EUGENE SALAZAR, OF SAN FRANCISCO, CALIFORNIA.

DESIGN FOR A BASKET.

56,769.

Specification for Design.

Patented Dec. 14, 1920.

Application filed May 22, 1920. Serial No. 383,577. Term of patent 7 years.

To all whom it may concern:

Be it known that I, EUGENE SALAZAR, a citizen of the United States, residing at San Francisco, in the county of San Francisco and State of California, have invented a new, original, and ornamental Design for Baskets, of which the following is a specification, reference being had to the accompanying drawing, form part thereof.

In the drawing:

Figure 1 is a side elevation of a basket showing my new design; and,

Fig. 2 is a plan view showing the same.

I claim:

The ornamental design for a basket, as shown.

EUGENE SALAZAR.
